UNITED STATES PATENT OFFICE.

HENRY J. SCHLACKS, OF CHICAGO, ILLINOIS.

OPERATING-ROOM FOR HOSPITALS.

1,134,161.

Specification of Letters Patent.

Patented Apr. 6, 1915.

Application filed April 13, 1911. Serial No. 620,943.

To all whom it may concern:

Be it known that I, HENRY J. SCHLACKS, a citizen of the United States, residing at Chicago, in the county of Cook and State 5 of Illinois, have invented certain new and useful Improvements in Operating-Rooms for Hospitals, of which the following is a specification.

This invention relates to operating rooms 10 for hospitals although it is not restricted to hospitals or even to operating rooms, the main object being to heat any room without permitting the air which comes directly from the heating means, to enter the room.

15 It is well recognized by the medical profession that the rooms in which operations are performed must be kept scrupulously clean and in an antiseptic condition and that a constant predetermined temperature 20 be maintained therein. Operating rooms as constructed prior to my invention have been heated by radiators located therein, but these radiators have been a fruitful source of infection because of the dust particles 25 and germs which collect on their rough surfaces and are subsequently distributed throughout the room by the convectional currents set up by the radiators. To overcome this danger the radiators are usually 30 covered at the time of an operation with sheets of textile material, but even this precaution is insufficient to prevent the dust and germs from being distributed throughout the room.

35 My present invention aims to eliminate this source of danger of infection by removing the radiators from the room entirely and heating the room indirectly through the 40 walls without permitting the air which comes directly in contact with the radiators to enter the room at all.

To accomplish this result I construct a room with double walls, leaving an air 45 chamber between them in which the radiators or other source of heat are located, the inner wall being relatively thin and of good heat conducting properties so that the heat will be transmitted therethrough to the interior of the room.

50 Another source of danger of infection in the ordinary operating room has been the light which is usually suspended directly over the operating table. The dust and 55 germs which collect on the light frequently

become dislodged and drop down into the open wound and thereby cause infection.

My present invention aims also to avoid this danger of infection by suspending the 60 light above a transparent plate arranged in the ceiling, so that any dust or germs dislodged therefrom can not enter the room.

My invention will be best understood by reference to the following description when 65 taken in connection with the accompanying drawings illustrating one preferred embodiment thereof.

Referring to the drawings—Figure 1 is a horizontal sectional view of an operating 70 room constructed in accordance with my invention; and Fig. 2 is a vertical sectional view taken on the line 2—2 of Fig. 1.

From the drawings it will be observed 75 that the room comprises an ordinary floor 5 preferably tiled, side-walls 6, rear walls 7, a front wall 8 and a ceiling 9. The vertical walls and the ceiling may be constructed in any approved manner and constitute the outer walls of the room. Doors 10 opening 80 into the adjacent rooms or halls may be located in the side and rear walls wherever they may be found necessary or convenient and the wall 8 is preferably provided with windows 11 of usual construction. The 85 structure thus far described does not differ materially from building constructions which have been in use prior to my invention.

Around the interior of the room and 90 spaced from the vertical walls I construct an inner wall 12 leaving an air chamber between the inner and outer walls. The inner walls are joined to the outer walls around the doors 10 and around the windows 13 95 disposed adjacent the windows 11 so as to form a continuous air chamber surrounding the room. The window-sills 14 are perforated as indicated at 15 to establish communication between the spaces between the windows and the air chamber beneath the sills, shutters being provided to close the perforations when desired. The compartments 16 between the ends of the window-sills communicate at both their upper and 100 lower ends with the air chamber and are separated from the spaces between the windows so that the air chamber will not be cooled by the opening of one of the outer windows. The inner walls 12 are also con- 110

tinued inwardly at 17 in parallel relation to the ceiling thereby continuing the air chamber around the ceiling as well as around the sides of the room. The inner walls are im-
5 perforate so that no communication is estab-
lished between the air chamber and the in-
terior of the room and are made relatively
thin and of material which is a good con-
ductor of heat so that heat from the air
10 chamber will be conveyed to the interior of
the room through these walls. The inner
walls, including the inner ceiling, are pref-
erably made of metal lathing coated with
plaster, but any other material having good
15 heat conducting properties may be employ-
ed instead, if preferred.

In the air chamber formed between the inner and outer walls are located the heating elements 18, these elements in the pres-
20 ent instance being shown in the form of steam or hot water radiators. The doors 19 are provided in the outer wall adjacent
25 the radiators so that the valves controlling the radiators may be manipulated by opening these doors from an adjoining room. Normally these doors are closed so that radiators are wholly inclosed in the air space surrounding the operating room. Air
30 is admitted to the space either through per-
forations in the bottom of the doors 19 or through other suitable inlet openings. The air surrounding the radiators is heated and circulates through the air chamber, suitable
35 ventilating flues 20 being provided in the ceiling to assist in maintaining a proper cir-
culation of the air and distribution of the heat throughout the chamber. It will be
40 evident that the air which comes directly in contact with the radiators and is more or less laden with dust particles and germs is prevented from entering the operating room itself, the heat from this air, however, being conducted to the interior of the room through the relatively thin heat conducting
45 inner walls. The convectional currents set up by the radiators are thus prevented from entering the room and the danger of infec-
50 tion from the air distributed by the radiators is thereby obviated. While I have shown the radiators as located directly in the air space surrounding the room, it will be
55 obvious that if the building is heated by a hot air furnace the hot air pipes may be connected with the air chamber and the heated air will be circulated around the chamber in a similar manner.

The inner walls and the ceiling are pref-
erably tiled or painted so that they may be
60 easily washed and disinfected and the ceil-
ing is relatively low, preferably not more than 7 to 9 feet above the floor, thus re-
ducing the wall space and making it easier to clean. A large plate-glass 21, prefer-
ably circular in form, is mounted in the

center of the ceiling over the operating table 65 and a light 22, which may be of any pre-
ferred type, is suspended above the glass. The lights which are used in this connection are customarily mounted so that they can be
70 swung from the interior of the room to bring the light directly over any part of the table. This movement of the light has heretofore caused dust particles and infectious
75 germs to fall upon the subject, but by position-
ing the light above the glass all dangers of infection from this source are eliminated.

From the foregoing it will be observed
80 that the operating room has a smooth in-
terior surface unbroken by radiators or
other heating elements so that all portions
85 of the room may be readily and thoroughly
washed and disinfected. The proper tem-
perature is maintained in the room by the
heat which is conducted through the inner
walls, while the air which directly contacts
90 with the heating elements is prevented from
entering the room itself, thus obviating dan-
gers of infection from this source and the
light above the operating table is suspended
95 above a plate in the ceiling so that no in-
fectious particles can drop therefrom onto
the subject.

It is thought that the invention and many
of its advantages will be understood with-
out further description and it is obvious
95 that various minor changes in the construc-
tion may be resorted to without departing
from the spirit or sacrificing any of the ma-
terial advantages of the invention.

I claim:

1. In a hospital building having a heating
system and an operating room provided
with inner supplemental side walls and a
supplemental ceiling spaced from the walls
and ceiling respectively of the building and
defining therewith a space surrounding said
side walls and ceiling of the room and sealed
from the interior of said room and in op-
erative relation to the heating system of the
building, there being a doorway leading
110 through the outer and inner walls to give
access to the interior of the room, the space
between the inner and outer walls being
sealed around the doorway.

2. A hospital building having a heating
system, and an operating room provided
with inner supplemental side walls and a
supplemental ceiling spaced from the walls
and ceiling respectively of the building and
defining therewith a space surrounding said
side walls and ceiling of the room and sealed
from the interior of said room for receiving
a temporary medium, there being a doorway
leading through the outer and inner walls
120 to give access to the interior of the room, the
space between the inner and outer walls being
sealed around the doorway and a cir-
culating coil located in said space between

- the inner and outer walls and in communication with the heating system of the building.
3. A hospital building having a heating system, and an operating room provided with inner supplemental side walls and a supplemental ceiling spaced from the walls and ceiling respectively of the building and defining therewith a space surrounding said side walls and ceiling of the room and sealed from the interior of said room for receiving a tempering medium, there being a doorway leading through the outer and inner walls to give access to the interior of the room, the space between the inner and outer walls being sealed around the doorway.
- 10 5. A hospital building having an operating room provided with inner supplemental walls spaced from the side walls and ceiling respectively of the building and defining therewith a space surrounding said side walls and ceiling of the room and sealed from the interior of said room for receiving a tempering medium, there being a doorway leading through the outer and inner walls to give access to the interior of the room, the space between the inner and outer walls being sealed around the doorway, a 40
- 15 5. A hospital building having an operating room provided with inner supplemental walls spaced from the side walls and ceiling respectively of the building and defining therewith a space surrounding said side walls and ceiling of the room and sealed from the interior of said room for receiving a tempering medium, there being a doorway leading through the outer and inner walls to give access to the interior of the room, the space between the inner and outer walls being sealed around the doorway, a 45
- 20 5. A hospital building having an operating room provided with inner supplemental walls spaced from the side walls and ceiling respectively of the building and defining therewith a space surrounding said side walls and ceiling of the room and sealed from the interior of said room for receiving a tempering medium, there being a doorway leading through the outer and inner walls to give access to the interior of the room, the space between the inner and outer walls being sealed around the doorway, a 50
- 25 5. A hospital building having an operating room provided with inner supplemental walls spaced from the side walls and ceiling respectively of the building and defining therewith a space surrounding said side walls and ceiling of the room and sealed from the interior of said room for receiving a tempering medium, there being a doorway leading through the outer and inner walls to give access to the interior of the room, the space between the inner and outer walls being sealed around the doorway, a 55
- 30 4. A hospital building having an operating room provided with inner supplemental side walls and a supplemental ceiling spaced from the walls and ceiling respectively of the building and defining therewith a space
